UNITED STATES PATENT OFFICE

2,535,505

DIE-CAST SLIDER PULL WITH FORMED
PIVOT BEARINGS

Louis H. Morin, Bronx, N. Y.

Application July 12, 1947, Serial No. 760,625

4 Claims. (Cl. 24—205.14)

1

This invention relates to the pull of sliders of separable fasteners employed to couple and uncouple the stringers of the fasteners. More particularly, the invention deals with a one-piece die cast pull device wherein the pivot bearing portions are so formed in casting the pull as to dispense with the necessity of drilling or otherwise forming the pull for reception of the pivot pin employed to pivotally couple the pull with the slider. Still more particularly, the invention deals with pulls of the class described including integral lock pins or elements adapted to extend into the channel of the slider in retaining the slider against movement along the stringers.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a perspective view of one form of pull which I employ.

Fig. 2 is a cross-sectional view through a separable fastener slider and through the pivot portion of a pull, similar to that shown in Fig. 1.

Fig. 3 is a partial section on the line 3—3 of Fig. 2.

Fig. 4 is a partial section on the line 4—4 of Fig. 3.

Fig. 5 is a view similar to Fig. 1 showing a modified form of pull; and

Fig. 6 is a view similar to Fig. 2 showing the pivot end of the pull of Fig. 5 and showing only part of the slider structure.

In Fig. 2 of the drawing, I have shown at 10 a slider, such as is well known in the art for coupling and uncoupling the stringers of separable fasteners. The stringers are not shown, for sake of clarity and in view of the fact that slider structures of the kind under consideration are well known in the art. At 11 I have shown the top wall of the slider, at 12 the bottom wall, these walls being joined at one end of the slider in a connecting frog or web 13, forming a channel 14 between the spaced walls. The top and bottom walls also have inturned side flanges 15 and 16, respectively, which define the channel 14. The top wall has a pair of upwardly extending lugs 17, 17', adjacent side edge portions thereof, the lugs having apertures, as at 18, 18', for the reception of a pivot pin 19. The wall 11 has an elongated aperture 20, adjacent the lug 17. In spaced relation to the lugs 17, 17', the wall 11 has a small aperture 21 positioned substantially as seen in Fig. 2 of the drawing. The upper surface of the wall 11, between the lugs 17, 17', has a concaved recess, as at 22, to compensate for free swinging or pivotal movement of the pivot end portion 23 of a pull 24.

2

The pivot end portion 23 has side bearings 25 and 26 which are substantially U-shaped in form, having openings 27 and 28, respectively, which open through the upper surface of the pivot end portion 23. Between the bearings 25 and 26, the upper surface of the pivot portion 23 has a curved hood portion 29 which conceals that part of the pivot pin 19 disposed between the bearings 25 and 26 or at least the major portion of this

spacing of the bearings.

It will be noted that the bearing 25 includes, as an integral part thereof, a downwardly extending pin or lock element 30 which is adapted to extend through the aperture 20 to normally enter the channel 14 to engage the fastener stringers in retaining the slider against movement thereon. The pin or element 30 joins the body portion 31 of the pull in an offset reinforcing part 32, note Fig. 3 of the drawing. This part does not extend into the channel. However, the aperture 20 is made sufficiently long to receive the part 32, as will clearly appear from a consideration of Fig. 3 of the drawing.

The under-surface of the body 31, adjacent the pivot end 23 and opening into said pivot end, has an elongated recess 33, the depth of which is increased to a slight extent by a raised boundary wall portion 34. The recess 33 is adapted to receive one end 35 of a coil spring 36 arranged upon the pivot pin 19 within the hood 29. The other end 37 of the spring extends into the aperture 21, as clearly seen in Fig. 2 of the drawing.

In Fig. 4 of the drawing is shown a cross-section through said part of the body 31 having the raised wall portions 34 around the recess 33. These walls are normally cast open in casting the pull and, when the spring end 35 is placed in the recess 33, the walls 34 are forced inwardly, as seen at 38, in said figure to partially close the recess 33 retaining the spring end 35 in fixed engagement with the body 31. It will be apparent that the spring 36 is tensioned to normally support the pull in the closed position, shown in Figs. 2 and 3 with the element 30 in the channel 14 in raising the pull or swinging the same on the pivot pin 19, the tension of the spring is increased so that, when the pull is released, the spring will automatically return the element 30 to its locked position.

The free end of the pull has an enlarged apertured head, as seen at 39, which forms a suitable finger grip portion, retaining the pull against accidental displacement from the fingers of the hand.

In Figs. 5 and 6 of the drawing, I have shown a slight modification and, in Fig. 6, the top wall 40 only of the slider is shown this wall having spaced apertured lugs 41, 41' for the reception of a pivot pin 42, this structure being the same as in Fig. 2. Between the lugs 41, 41' the slider wall

is recessed, as at 43, the same as the recess 22 and the wall of the slider has one elongated aperture 44 receiving the lock element 45 of a pull 46, as well as the end 47 of a spring 48. The primary difference between the pull of Figs. 5 and 6 and that of the other figures resides in the fact that a center elongated bearing 49 is provided instead of the two end bearings 25, 26. The element 45 is integral with the bearing 49 and, instead of a single hood portion, as at 29, the upper outer surface of the pull has two side hood portions 50, 51 which partially conceal the pivot pin 42. The hood 50 also conceals the coil spring 48 arranged on the pin 42. The hood 50 has a notch 52 for receiving the other end 53 of the spring 48. Between the hoods 50, 51, the pivot end of the pull has a recess 54 opening outwardly in the same manner, as the recessed 27 and 28.

By constructing the pivot ends of pulls in the manner disclosed, it will be apparent that the bearing and hood portions may be formed in die casting the pulls thus dispensing with the need of drilling or otherwise forming said pivot portions in attaching the pulls to the pivot pins. In other words, the pins 19, 42 are simply passed through the pivot portions of the respective bearings, namely 25, 26 and the bearing 49 and then riveted over or otherwise secured, as indicated at 55 in Fig. 2 and 56 in Fig. 6. It will, of course, be understood that the springs 36 and 48 are attached to the pins before they are headed over and in assemblage of the pins with the pull.

By virtue of this construction, the cost of producing a pull is materially simplified in that the handling and time required to form pivot pin holes in the bearing or pivot ends of pulls is dispensed with. At the same time, my improved construction provides secure and firm mounting of the pulls on the pivot pins.

It will be recognized that in its broader aspects the invention is indifferent to whether or not a spring is utilized and that the described adaptation of the invention to a slider pull is illustrative only. In general, the pull can be thought of as a hinge plate having one or more hinge lugs (49 in Fig. 6 and 25, 26 in Fig. 1), protruding from one face of the plate adjacent one of its edges. What adapts the construction to economical manufacture by casting and eliminates the need for drilling or piercing is the fact that the hinge pin hole is constituted by a slot penetrating the face of the plate and the lug or lugs to an appropriate depth (as is convenient in casting) the length of the slot being greater than the width or thickness of the lug, so that the surplus slot length insures a clean cut-hole or opening to receive the hinge pin. Preferably and as illustrated the lug-bearing portion 29 of the hinge plate is of arcuate form and the lug or lugs protrude from the concave side.

Having fully described my invention, what I claim as new and desire to secure by Letters Patent is:

1. The combination with a slider having spaced lugs upstanding from its upper surface of a slider pull comprising a plate-like body portion having a thickened end portion extending transversely of one end of said body portion, said end portion being of a width to enter between the said spaced lugs, and a hinge lug projecting from the under side of said end portion, said lug being of a width less than the width of the body portion and having a hinge pin opening therethrough to accommodate a hinge pin parallel to the plane of the

body portion, said opening constituted by a slot penetrating the face of the body portion and the hinge lug to a depth to accommodate the hinge pin, the length of the slot, widthwise of the body portion, being greater than the width of the lug, said surface of the slider having an aperture therethrough and said hinge lug having a locking projection penetrating said aperture, a hinge pin extending through both said spaced lugs and said hinge lug, and a coil spring on said pin between said spaced lugs, one end of said coil spring being interlocked with said upper surface of the slider.

2. The combination with a slider having spaced lugs upstanding from its upper surface of a slider pull comprising a plate-like body portion having an enlarged end portion extending transversely of one end of said body portion, said end portion being of a width to enter between the said spaced lugs, and a hinge lug projecting from the under side of said end portion, said lug being of a width less than the width of the body portion and having a hinge pin opening therethrough to accommodate a hinge pin parallel to the plane of the body portion, said opening constituted by a slot penetrating the face of the body portion and the hinge lug to a depth to accommodate the hinge pin, the length of the slot, widthwise of the body portion, being greater than the width of the lug.

3. The combination with a slider having spaced lugs upstanding from its upper surface of a slider pull comprising a plate-like body portion having an enlarged end portion extending transversely of one end of said body portion, said end portion being of a width to enter between the said spaced lugs, and a hinge lug projecting from one side of said end portion, said lug being of a width less than the width of the body portion and having a hinge pin opening therethrough to accommodate a hinge pin parallel to the plane of the body portion, said opening constituted by a slot penetrating the face of the body portion and the hinge lug to a depth to accommodate the hinge pin, the length of the slot, widthwise of the body portion, being greater than the width of the lug.

4. A pull for sliders of separable fastener stringers, said pull comprising an elongated body having a pivot end and a fingerpiece end, the pivot end of the pull having on opposed surfaces thereof hood and bearing portions arranged transversely of the pull, the hood and bearing portions being alternately closed on opposed surfaces of the pull thereby leaving other opposed surfaces open, inner surfaces of said hood and bearing portions being spaced, one with respect to the other to form a pivot pin receiving passage throughout the full width of the pull for pivotal mounting of the pull, a pin on which said pull is mounted, and the inner surface of a hood portion being widely spaced from said pin when said pin engages a bearing portion.
